United States Patent Office

Des. 210,940
Patented May 7, 1968

210,940

SEAT

Charles Eames, Venice, Calif., assignor to Herman Miller,
Inc., Zeeland, Mich., a corporation of Michigan

Filed Jan. 30, 1967, Ser. No. 5,599

Term of patent 14 years

(Cl. D15—8)

FIG. 1.

FIG. 2.

FIG. 3.

FIG. 4.

FIG. 1 is a side, perspective view of the novel design for a seat;

FIG. 2 is a frontal perspective of the seat illustrated in FIG. 1;

FIG. 3 is a side-elevational view of the novel design; and

FIG. 4 is a cross-sectional view taken along plane IV-IV of FIG. 2.

I claim:

The ornamental design for a seat, substantially as shown.
